UNITED STATES PATENT OFFICE

2,257,353

SHEAR GRINDING MECHANISM

Bogota Strezoff, Minneapolis, Minn.

Application October 12, 1939, Serial No. 299,114

1 Claim. (Cl. 51—125)

This invention relates to grinding and sharpening apparatus and is particularly adaptable for use in connection with the sharpening of the blades of shears or scissors.

One of the objects of my invention is to provide a shears sharpener in which the blade being sharpened will be held in proper relation to a rotary sharpening wheel so that a regular and properly inclined face is produced at the cutting edge.

Another object of the invention is to provide a sharpener or grinder wherein the pressure of the blade against the wheel can be varied at will and wherein such variation is produced through hand manipulation so that the operator can actually feel the amount of pressure applied.

A further object of the invention is to provide a blade holding means which enables quick and simple insertion and removal of the blade and wherein the blade holder is movable relative to the grinding wheel to further facilitate insertion and removal.

These and other objects and advantages of the invention will more fully appear from the following description made in connection with the accompanying drawing, wherein like reference characters refer to the same parts throughout the views, and, in which:

Fig. 1 is a view in elevation of one embodiment of my invention;

Fig. 2 is a plan view thereof;

Fig. 3 is a section taken approximately on the line 3—3 of Fig. 1;

Fig. 4 is an elevation of another embodiment of the invention;

Fig. 5 is a side elevation of a blade clamp construction common to both embodiments; and

Fig. 6 is a section taken approximately on the line 6—6 of Fig. 5.

In Fig. 1 there is shown a bracket B which has an upper lateral extension 7 and a lower lateral extension 8. Threaded vertically through the lower extension 8 is a thumb screw 9 which rotatably carries a clamp element 10. The bracket is adapted to be slipped upon the edge of the table or bench 11 and the thumb screw 9 tightened to firmly grip the table edge between the clamp element 10 and the lateral extension 7 on the bracket B.

Rotatably supported on and extending upwardly from the upper portion of the bracket B is a vertical shaft 12 whose upper end carries a wheel 13 having an upper flat abrasive surface

14. Adjacent the lower end of the shaft 12 the bracket B is provided with a cut-out 15 within

which is located a beveled gear 16 secured to said shaft 12. This gear is relatively small and is adapted to mesh with a larger gear 17 mounted for rotation with a shaft 18 journalled horizontally in the lower portion of the bracket B. A hand crank 19 is also secured upon said shaft 18 and when it is rotated it will in turn rotate the gears 16 and 17, the vertical shaft 12 and the rotary wheel 13.

10 A bracket C is provided at one end with a partially circular portion 20 which carries a pair of inwardly turned lugs 21. The curved bracket end 20 is adapted to fit around the upper portion of the main bracket B which is concentric to the vertical shaft 12 as best shown at 22 in Fig. 3. The lugs 21 are adapted to be fitted into appropriate detents in said rounded upper bracket portion 22. The bracket C extends outwardly in a horizontal direction from the portion 22 of the main bracket B and is provided with an upwardly turned outer end 23 which is rolled as at 24 to provide a tubular bearing or pivot portion. The two ends of the tubular bearing 24 are adapted to receive arms 25 which extend outwardly from the adjacent sides of a substantially U-shaped blade clamp 26 at one end of said clamp. The clamp 26 is preferably of sheet metal and the extending arms 25 are preferably rounded at their ends so that they will better fit the tubular turned end 24 on the bracket C.

20 The blade clamp 26 is adapted to move in pivotal relationship to said bracket C. The blade clamp, as stated above, is sheet metal and preferably resilient so that it will assume the shape shown in Figs. 1 and 6 when no external force is applied thereto. It is of generally inverted U-shape and the body of the clamp is tilted at an angle to the vertical so that a blade held therein will be retained in proper relation to bevel the cutting edge of the shears blade. Central portions of the clamp 26 are partially cut out and bent upwardly to provide levers or grips 27 so that the clamp can be opened slightly by pressure on said levers toward each other. The clamp is pressed open in order to facilitate insertion of a blade such as the blade 28 shown in Figs. 1 and 2. To reinforce the sheet metal clamp 26 I provide a wire spring element 29 which, as shown, extends along opposite outer sides of clamp 26 and over said clamp as at 29a. This spring is retained upon the clamp by small tongues 30 which preferably are punched out of the metal sheet of the clamp itself.

25 As shown in Fig. 2 the bracket C is curved slightly at the outer end of the horizontal por-

tion thereof so that the blade clamp 26 will not pass over the center of the wheel at the end of the vertical shaft 12. Furthermore, the tilting of the blade clamp above described is such that the upper edge of the clamp is nearest the end of said shaft 12 so that the clamp will strike against the shaft as it is swung toward the center of the abrasive wheel and the edge of the blade held in the clamp will not be injured. There is no pivotal swinging movement toward and away from the vertical shaft 12 in the structure shown but the clamp is relatively loosely supported so that the blade edge will lie flat against the abrasive surface 14 and it is entirely possible at times to bring the clamp into contact with the vertical shaft 12.

When the device is operated it may be set in motion by turning of the crank 19 with either hand leaving the other hand free to manipulate the blade holding clamp 26 as desired. It is contemplated that the clamp bracket C can be curved at its outer end to bring the clamp 26 on either side of the vertical shaft 12.

In Fig. 4 there is shown an embodiment wherein the abrasive wheel is placed vertically rather than horizontally as in the embodiment illustrated in Figs. 1 and 2. In this embodiment the main bracket D extends vertically from the table or bench 11 a greater extent than the bracket B in the other form and the abrasive wheel 31 which is mounted in a vertical plane is supported by a horizontal shaft 32 which is journaled in the top of said bracket D. A small pinion 33 meshes with a larger gear 34 provided with a crank 35. The gear 34 and crank 35 are mounted on a horizontal stub shaft 36 which is journaled in the main bracket D. As shown a detachable screw clamp is formed at the bottom of the bracket D as in the other embodiment described.

A blade clamp 37 which is constructed the same as the clamp 26 in Fig. 1 is mounted relative to the abrasive surface of the wheel 31 to produce grinding or sharpening of a shears blade in exactly the same manner as before described. There is a small bracket 37, however, which is different from the bracket C shown in Fig. 1, and it comprises merely a right-angled element having one end rigidly secured as by screws to the main bracket D and one arm of which extends outwardly adjacent the edge of the wheel 31. The outwardly extending arm of the bracket 37 is provided with a substantially cylindrically turned portion 38 similar to the end 24 on the bracket C, and the blade clamp 36 is mounted on the bracket 37 in the same manner as its pivotal connection with bracket C. The general operation of each of the two forms of the invention is the same and the horizontal and vertical positions of

the grinding wheel are provided for the reason that some might find it more convenient to work on a device with a wheel in one or the other of the two positions.

From the foregoing description it will be seen that I have provided a simply constructed yet efficient apparatus for grinding and sharpening the blades of shears wherein the blade can be easily slipped into the blade clamp either longitudinally through the open end of the clamp or it may be slipped into the open bottom of the clamp after the clamp has been swung away from the grinding wheel to some extent. The clamp can be pressed with varying degrees of force to make a heavy or a light cut on the blade edge and it is preferred that the brackets C or 37 be resilient to some extent so that there will be proper contact between the cutting edge of the blade and the grinding wheel. It is a relatively compact device which can be quickly set upon an edge of a table or bench and it can be just as readily detached and stored. While the blade clamp is relatively flexibly mounted it will because of its tilted position produce a proper and uniform angularity at the cutting edge so that upon successive sharpenings this angle will be maintained. Due to the gear arrangement shown the device can be hand operated and the grinding wheel will rotate with considerable speed. For that reason a relatively fine abrasive face can be provided on the wheel for the production of a smooth and satisfactory shears edge.

It will, of course, be understood that various changes may be made in the form, details, arrangement and proportions of the various parts throughout the views without departing from the scope of my invention.

What is claimed is:

40 In a shears sharpener and the like, a rotary sharpening wheel having a flat working face, a bracket supporting said wheel for rotation, a work clamp support connected to said bracket and having its outer end terminating adjacent the edge of said wheel, said outer end having an aperture therein on an axis parallel to the working face of said wheel, and a work clamp comprising an elongated jaw member adapted to lie across and closely adjacent the working face of said wheel, said jaw member having a pair of resilient arms extending outwardly from an end thereof, said arms having their ends turned inwardly toward each other and resting in the aperture in said clamp support, and said jaw member having cooperating relatively thin jaw portions whose longitudinal edges are flared apart to facilitate insertion of a shears blade therebetween.

BOGOIA STREZOFF.
